UNITED STATES PATENT OFFICE.

FRIEDERICH MÜLLER, OF ELIZABETH, NEW JERSEY, ASSIGNOR TO NILES-BEMENT-POND COMPANY, OF JERSEY CITY, NEW JERSEY.

MACHINE-TOOL.

1,139,794.

Specification of Letters Patent. Patented May 18, 1915.

Application filed May 27, 1904, Serial No. 210,024. Renewed November 29, 1905. Serial No. 289,668.

To all whom it may concern:

Be it known that I, FRIEDERICH MÜLLER, a citizen of the United States, residing at Elizabeth, in the county of Union and State 5 of New Jersey, have invented certain new and useful Improvements in Machine-Tools, of which the following is a specification, reference being had therein to the accompanying drawings.

10 This invention relates to an improvement in automatic machine tools, and is designed more particularly for embodiment in that class of milling machines intended for cutting longitudinal or spiral grooves in taps 15 and drills.

The invention has for its object to increase the speed and effectiveness of action of the cutters upon the work, to save time in the adjustment of the work in the machine, to 20 insure accuracy in the finished product, and render the same independent of special care or skill on the part of the operator.

In accordance with this invention, a plurality of rotary cutters are mounted to operate 25 in a substantially single plane and the same are symmetrically arranged around a central line extending substantially at right angles to said plane, means are provided for supporting at their opposite ends the blanks 30 to be grooved, the blank engaging members of said blank supporting means being operatively arranged on opposite sides of the plane of the cutters to support the blanks with their axes coincident with said central 35 line and means are provided for producing a relative movement between the cutters and the blank lengthwise of the blank. These and other features of the invention will be made clear by reference to the embodiment 40 thereof illustrated by way of example in the drawings annexed, in which—

Figure 1 is a side elevation of a milling machine of the class described, with the lower portion of the column supporting the bed removed and the upper portion of the machine partially in section; Fig. 2 is a transverse section of the same in a plane intermediate the cutters and the adjustable work-engaging center, and Fig. 2^a is a transverse section of an adjustable bracket for one of the cutter spindles. Fig. 3 is a plan of the machine with the cutter-actuating shaft and its bracket removed to expose the parts beneath. Fig. 4 is a rear end view of

the machine. Fig. 5 is a detail plan view 55 showing the clutch and feed throw-out mechanisms, and Figs. 6 and 7 are, respectively, front and transverse sectional views of the feed throw-out mechanism.

The machine is shown provided with a 60 bed 1 supported upon the usual column 2 and provided with a frame 3 carrying the feed-shaft 4 and feed-cam 5 mounted thereon, and provided with suitable guide-ways 6 to which are slidably fitted the carriages 7 65 and 8 for the work-supporting brackets 9 and 10, respectively, these carriages being rigidly connected together by means of the bar 11 through which they are given corresponding sliding movements upon the slide-ways 6 by means of a roller-stud 12 depending from the carriage 7 and entering the cam-groove 13 of the cam-cylinder 5. Upon the frame 3 is rigidly mounted the gearing 70 supporting post 14 with hollow hub 15 and 75 the tool-carrying member comprising the vertical carrying plate 16 whose lower edge rests upon the table of the frame 3 and whose upper portion is supported by the curved braces 17 rising also from the bed 3. 80 The tubular hub 15 is provided with suitable bushings to which is fitted the fixed spindle 18 secured at one end in its socket in the bracket 10 by means of the set screw 19 and having at its opposite end the conical work-engaging center 20 coöperating with the 85 movable center 21 carried by the sliding spindle 22 in the split barrel 23 of the bracket 9 and provided with the usual operating hand-wheel 24 and clamp provided 90 with the lever 25. To the exterior of the forward end of the hub 15 is fitted a bushing 26 upon which is mounted the loose sleeve 27 formed at one end with the cutter-actuating gear-wheel 28. The vertical tool-carrying 95 plate 16 is shown provided with four pairs of parallel undercut gibbs 29 disposed in directions tangential of the gear-wheel 28 to which are fitted the four sliding cutter spindle-heads 30 each of which is provided 100 with a threaded hole entered by an adjusting screw 31 having its end portion adjacent to the square head 32 swiveled to a forked lug 33 formed upon the plate 16. Each of the brackets 30 is provided with a cutter 105 spindle 34 mounted in suitable bearings 35 intermediate which it carries a fixed spiral gear 36 and is provided upon its opposite

end with a suitable milling cutter 37. Each spindle-head 30 also carries a short shaft 38 passing through the same and through a suitable aperture in the carrying plate 16, 5 upon one end of which is disposed a spiral gear 39 meshing with the gear 36 and upon the opposite end a spur gear 40 meshing with the gear 28 upon the sleeve 27. By reason of the tangential arrangement of the gibs 29 in respect of the gear 28, a limited 10 adjustment of the cutter-spindle-heads 30 by means of the adjusting screws 31 is permitted without materially affecting the intermeshing of the gears 28 and 40, so that the 15 cutters are capable of adjustment toward and from the axial line of the centers 20 and 21 without a corresponding adjustment of their entire actuating means.

The common intermediate actuating gear 28 derives its motion from the cutter-driving shaft 41 carrying the pulley 42 by means of a pinion 43 upon said shaft meshing with a gear 44 mounted rigidly upon the hub of the gear 28, whereby motion 25 communicated from the source of power to the pulley 42 is communicated at a reduced speed to the gear-wheel 28 from which the several cutters derive their motion in operating upon the threaded tap *a* carried by 30 the centers 20 and 21.

As indicated in Figs. 1 and 3, the fixed spindle 18 is provided in its forward or operative end portion with a series of longitudinal clearance grooves or cuts 20^x corresponding in number and position with the milling cutters 37 in order to prevent the interference of such spindle with the cutters when in initial relation therewith immediately before and after a groove-cutting 40 operation upon the stock, as the tap *a*. These clearance cuts are essential, for the reason that the grooves to be cut in a drill or tap necessarily extend from the extremity of the operative portion of the same, while 45 the spindle or center for sustaining the latter must be of such size as to give the necessary stiffness to insure the proper support of the work.

The power for driving the feeding mechanism is communicated through the pulley 45 mounted upon the shaft 46 carrying the loose clutch collars 47 and 48, the former of which is connected with the worm-shaft 49 by means of the intermeshing gears 50 and 51, and the latter of which clutch collars is 55 connected with the said worm-shaft by means of the gears 52 and 53 upon the respective shafts and the intermediate gear 54 intermeshing with said gears. Intermediate the clutch-collars 47 and 48 is disposed the sliding clutch collar 55 splined to the shaft 46 and provided with an annular groove 56 entered by the spherical end of a pin 57 carried by a shift-lever 58. The sliding clutch collar 55 is provided with the

usual teeth upon each end which are adapted to interlock alternately with corresponding teeth upon adjacent ends of the loose collars 47 and 48. The gears 50 and 51 and the gears 52, 53 and 54 are so arranged and proportioned that when the sliding collar 55 is in engagement with the collar 47 the worm-shaft 49 will be rotated forwardly at a comparatively slow speed to produce a feeding movement of the work-holding member, while the shifting of the clutch collar 55 out of engagement with the collar 47 and into engagement with the collar 48 causes the rotation of the worm-shaft 49 in the reverse direction and at a greatly increased speed to effect the return movement of the work-holding member after a cutting operation.

The worm-shaft 49 carries a worm 59 which meshes with a worm-wheel 60 fixed upon the cam-shaft 4 and provided with a radially movable section consisting of a block 61 fitted in a radial slot or guide-way 62 of the worm-wheel and provided upon its outer edge with a series of worm-teeth 90 complementary to the peripheral teeth upon the body of the worm-wheel, such block being held from lateral displacement by means of the cheek-plates 63 and 64 the latter of which is provided with a slot through 95 which extends a lateral pin 65 carried by the block 61.

The angular starting lever 66 pivoted at 67 to a fixed bracket 68 upon the frame 3 has its outer end portion connected by means of a link 69 with the shift-lever 58 pivoted at 70 to the said bracket 68, and to the outer end of said starting lever is pivoted at 71 a reciprocating cam-rod 72 the beveled head 73 of which is adapted to engage the pin 65 to raise the toothed portion of the block 61 into engagement with the worm 59 when the machine is started.

The rear face of the worm-wheel 60 is provided with an undercut slot 74 to which is fitted the similarly shaped head 75 of a screw-stud 76 provided with clamp-nut 77. The screw-stud 76 is circumferentially adjustable in the slot 74, its path of movement in the rotation of the worm 60 being such as to enable it to engage the tail of a latch-lever 78 mounted upon a fixed stud 79 on the frame 3 and having its operative end formed with a hook 80 adapted to engage a tooth 81 upon the outer extremity of the angular portion of the starting lever 66, a spring 82 being provided to maintain the latch-lever 78 normally in engagement with the starting lever 66.

In each of the figures of the drawings, excepting Fig. 4, the several parts of the machine are represented in the positions which they assume at the end of a groove-cutting operation, the starting lever 66 being shown in full lines in retracted position,

with the clutch member 55 in engagement with the member 48 for effecting the backward rotation of the worm 59, the cam-rod 72 being retracted to permit the worm-wheel section 61 to drop by gravity or to be forced by engagement of the pin 65 with the stationary cam-piece 83 secured to the frame 3 inwardly toward the cam-shaft 4 so as to lie out of engagement with the actuating worm as the worm-wheel 60 returns to initial or starting position, in which the work-holding member assumes its initial position with the grooved operative end of the tap *a* just beyond the cutters 37 in readiness for removal.

To effect a succeeding operation of the machine, the movable center 21 is backed off by suitable manipulation of the clamp-lever 25 and hand-wheel 24 for the removal of the tap *a*, which is replaced by an ungrooved tap, when the center 21 is advanced upon the same and secured in operative engagement therewith in the usual manner. The starting lever 66 is then thrown forwardly into the dotted line position represented in Fig. 5, which throws forward the shift lever 58 to couple the clutch collars 47 and 55 for communicating to the worm-shaft 49 a forward feeding movement, and simultaneously advances the cam-rod 72 whose head 73 engages the pin 65 and raises the worm section 61 into engagement with the rotating worm 59, whereby the forward movement of the worm-wheel 60, cam-shaft 4 and cam 5 are initiated, and the feed of the sliding brackets 9 and 10 commenced to bring the tap into operative relation with the continuously rotating cutters 37. This feeding movement continues until the worm 60 has rotated to the point indicated in Fig. 4, when its tripping stud 76 engages the latch-lever 78 and tilts the latter in opposition to its spring 82, and thereby releases the starting lever 66, which is returned to initial position under the action of the spring 84 interposed between the same and a pin 85 upon the frame 3. This movement of the starting lever causes the shifting of the clutch-member 55 from engagement with the collar 47 to engagement with the collar 48 for reversal of the direction of rotation of the worm-shaft 49 and simultaneously withdraws the cam-rod 72 to remove its head 73 from the circular path of movement of the pin 65 so as to enable the toothed portion of the worm-wheel section 61 to recede from the periphery of the worm-wheel under the action of the stationary cam 83 upon the pin 65, whereby, as the worm-wheel turns to initial starting position the worm runs out of engagement with the teeth of the same and the latter comes to rest in readiness for a succeeding operation.

Although the feed throw-out device, comprising the radially movable worm-wheel

section 61, and the cam-rod 72 operated manually to shift it into operative position and automatically to permit its return to inoperative position in respect of the body of the worm-wheel, will operate equally well whether the worm 59 rotates continuously in one direction or alternately in opposite directions, the employment of means for reversing the direction of rotation of the worm, and hence of the cam-shaft, is evidently advantageous as it is thereby made practicable to provide for a feeding movement of the work-supporting member to correspond with the length of tap or other stock to be grooved, the circumferential adjustment of the tripping stud 76 providing for the operation of so much only of the entire length of the cam-groove 13 as is necessary to communicate the requisite feeding movement to the work.

It will be observed that only a single manual actuation of the starting lever 66 is necessary in each operation of the machine, the return of such lever to initial position being effected automatically, and the final interruption of the feed-returning movement being accomplished independently of such automatic shifting of the lever 66.

While I have shown herein the movable work-engaging center 21 as forming a part of a common form of lathe tail-stock, adjustable upon its bed 7 by means of the usual clamp-bolt 86, it is evident that this may be replaced by a work-holder constructed in accordance with my application Serial No. 207,506, filed May 11, 1904, or by any other suitable or well-known form of work-holding member provided with means for rotating the work during the longitudinal feed of the same, so that the operation of the cutters will produce spiral grooves, in case the machine is to be used in making twist-drills.

I have not claimed herein the feeding mechanism herein shown and described, as the same forms the subject of my application, Serial No. 225,617, filed September 23, 1904.

Having thus set forth the nature of my invention, what I claim herein is,—

1. A milling machine including in combination, a plurality of rotary cutters symmetrically arranged on independent axes around a common center, means for rotating said cutters, means for supporting at their opposite ends the blanks to be milled, said supporting means including a pair of oppositely arranged blank engaging members and a guide for one of said members in fixed relation to the plane of and concentric with said cutters and means for producing a relative feeding movement between the cutters and the blanks lengthwise of the latter.

2. A milling machine including in com-

5 combination, a plurality of rotary cutters symmetrically arranged on independent axes around a common center, means for supporting at their opposite ends the blanks to be milled, said supporting means including a pair of oppositely arranged blank engaging members and a guide for one of said members in fixed relation to the plane of and concentric with said cutters, means 10 mounted on said guide for rotating said cutters, and means for giving the blank engaging members a feeding movement with relation to the cutters and guide.

3. A groove milling machine including 15 in combination a plurality of rotary cutters mounted on independent axes to operate in a single plane and symmetrically arranged around a central line extending at substantially right angles to said plane, means for 20 supporting at their opposite ends the blanks to be grooved, said supporting means including a pair of oppositely arranged rigidly connected blank engaging spindles, a stationary guide member for one of said spindles, located adjacent to the plane of and in concentric relation with said cutters, means for producing a relative movement between said spindles to engage the blanks and means for simultaneously moving the 25 spindles endwise with relation to the cutters and guide.

4. A milling machine including in combination, a work-holding member comprising a pair of rigidly connected brackets, 30 one of which carries a movably mounted work engaging spindle, an intermediate tool carrying member comprising a bracket formed with an opening one of said members being movable relative to the other, a plurality of rotary cutters arranged on independent axes around a common center and carried by said tool carrying member, a support having a rigid relation to said tool-carrying member and provided with a guide 35 disposed in axial alinement with the opening in said tool-carrying member, and a work-engaging spindle fitted to and passing through said guide and the opening in the tool carrying member and rigidly mounted 40 in the other of said work-holding brackets.

5. In a milling machine, the combination with the frame, a work-holding member comprising a pair of rigidly connected brackets each carrying a work-engaging 45 spindle, and an intermediate tool-carrying member comprising a bracket formed with an opening, the one of said members being movable relatively to the other upon said frame, a post provided with a hollow hub 50 through which and the opening in the tool-carrying member one of the work-engaging spindles is projected from its holding bracket, an actuating gear mounted upon said hollow hub, a plurality of cutter 55 spindle-heads mounted upon said tool-car-

rying member and provided each with a rotary cutter and connected mechanism comprising a gear meshing with said actuating gear, means for rotating said actuating gear, and means for communicating feeding 70 movements to the said movable member.

6. In a milling machine, the combination with the frame carrying relatively movable work-holding and tool-carrying members, of a hub mounted in fixed relation to said tool-carrying member, an actuating gear mounted thereon, a plurality of cutter spindle-heads mounted upon said tool-carrying member and provided each with a cutter and connected mechanism comprising a gear meshing with said actuating gear, said spindle-heads being adjustable each in a direction tangential to said actuating gear, means for driving said actuating gear, and means for communicating feeding movements to the movable member carried by said frame.

7. In a milling machine, the combination with a tool-carrying member and an actuating gear mounted in fixed relation thereto, of a plurality of concentrically arranged cutters, spindles by which said cutters are carried, intermediate spindles carrying gears meshing with the common actuating gear and connected with the cutter spindles by means of intermeshing angular gears, cutter spindle-heads mounted upon said tool-carrying member adjustably in directions tangential to said common actuating gear, and means for driving said actuating 100 gear.

8. In a milling machine, the combination with the frame, of a tool-carrying member comprising a bracket and a guiding hub in fixed relation thereto, a plurality of tool-carrying spindles mounted upon said member tangentially in respect of said guiding hub, a rotary tool upon each said spindle in radial relation to said hub, a work-holding member comprising a pair of rigidly connected brackets each carrying a work-engaging spindle the outer portion of one of which is passed through and supported by said guiding hub and is formed at its outer end with a plurality of clearance cuts each for 110 its respective rotary tool, means for actuating said tool-carrying spindles, and means for communicating feeding movements to one of said members relative to the other.

9. A machine for grooving tap blanks and the like, including, in combination, blank-supporting means including blank-centering members, a plurality of cutters symmetrically arranged relative to the axis defined by said centering members, the cutting planes of said cutters being substantially identical, said centering members being located at opposite sides of said cutters, respectively, means for rotating said cutters in unison, and automatic means for effecting a 120

125

130

predetermined extent of relative movement between said cutters and the blank-centering members lengthwise of the blank.

10. A machine for grooving tap blanks and the like, including, in combination, a plurality of pairs of oppositely arranged independent cutter-carrying spindles, said pairs being symmetrically arranged with reference to a common center so that the cutters operate in a single plane, means for driving said spindles in unison, blank-supporting means including blank-centering members located at opposite sides of the cutters, and automatic means for effecting a predetermined extent of relative movement between the cutters and the blank lengthwise of the blank.

11. A machine for grooving tap blanks and the like, including, in combination, a plurality of pairs of oppositely arranged independent cutter-carrying spindles, said pairs being symmetrically arranged with reference to a common center so that the cutters operate in a single plane, means for driving said spindles in unison, blank-supporting means including blank-centering members located at opposite sides of the cutters, automatic means for effecting relative movement between the cutters and the blank in a predetermined direction lengthwise of the blank while cutting, and means adapted to automatically arrest movement in said direction and cause relative movement between the cutters and the blank lengthwise of said blank in the opposite direction.

12. A machine for grooving tap blanks and the like, including, in combination, a plurality of pairs of oppositely arranged independent cutter-carrying spindles, said pairs being symmetrically arranged with reference to a common center so that the cutters operate in a single plane, means for driving said spindles in unison, blank-supporting means including blank-centering members located at opposite sides of the cut-

ters, automatic means for effecting relative movement between the cutters and the blank in a predetermined direction lengthwise of the blank while cutting, and means adapted to automatically arrest movement in said direction and cause relative movement between the cutters and the blank lengthwise of said blank in the opposite direction, said last-mentioned means comprising coöperative clutch members, a work-feeding member and trip devices coöperatively associated with said members.

13. In a tap grooving machine, the combination with a plurality of cutters symmetrically arranged around a center, means for rotating said cutters, means for supporting a tap blank at its opposite ends and on opposite sides of the cutters, said supporting means including a work-engaging spindle having a clearance groove for each of said cutters, and means for producing a relative movement between the cutters and the blank lengthwise of the blank.

14. In a tap grooving machine, the combination of a plurality of rotary cutters symmetrically arranged around a center, means including a member arranged concentrically with the cutters for rotating the cutters, means for adjusting the cutters inwardly and outwardly with relation to said center, means for supporting a tap blank at its opposite ends and on opposite sides of the cutters, said supporting means including a work-engaging spindle having clearance grooves for said cutters, and means for producing a relative movement between the cutters and the blank lengthwise of the blank.

In testimony whereof, I have signed my name to this specification, in the presence of two subscribing witnesses.

FRIEDERICH MÜLLER.
